(57) **CLAIM**

The ornamental design for a speaker for television receiver, as shown and described.

DESCRIPTION

FIG. 1 is a perspective view of a speaker for television receiver showing our new design;

FIG. 2 is a front view thereof;

FIG. 3 is a left side view thereof, and the right side view being a mirror image thereof;

FIG. 4 is a top plan view thereof, and the bottom plan view being a mirror image thereof;

FIG. 5 is a partially enlarged view thereof, taken from the lower middle part of FIG. 2; and,

FIG. 6 is a partially enlarged view thereof, taken from the lower left part of FIG. 2.

The dot-dash broken line portions of FIGS. 2, 5, and 6 are included to show partially enlarged views only and form no part of the claimed design.
